(57) **CLAIM**

The ornamental design for a broom, as shown and described.

DESCRIPTION

2. Broom

2.1 Perspective (Top)

2.2 Perspective (Bottom)

2.3 Front

2.4 Back

2.5 Left

2.6 Top

2.7 Bottom

Right side view was omitted because it is a mirror image of the left side view; the parts colored in dark grey form no part of the claimed design.

1 Claim, 7 Drawing Sheets

2.1

2.2

2.3

2.4

2.5
